UNITED STATES PATENT OFFICE.

JOSEPH EVANS, OF YOUNGSTOWN, OHIO.

DESIGN FOR A DIPPING SPOON.

Application filed March 17, 1928. Serial No. 25,890. Term of patent 7 years.

To all whom it may concern:

Be it known that JOSEPH EVANS, a citizen of the United States of America, residing at Youngstown, in the county of Mahoning and State of Ohio, has invented a new, original, and ornamental Design for Dipping Spoon, of which the following is a specification, reference being had to the accompanying drawing, forming part thereof.

Figure 1 is a top plan view of a dipping spoon, showing my new design.

Figure 2 is a side elevation of a dipping spoon, showing my new design.

Figure 3 is a cross section taken on line 3—3 of Figure 2.

Figure 4 is a cross section taken on line 4—4 of Figure 2.

Figure 5 is a cross section taken on line 5—5 of Figure 2.

Figure 6 is a cross section taken on line 6—6 of Figure 2.

I claim:

The original design for a dipping spoon, as shown.

In testimony whereof I affix my signature.

JOSEPH EVANS.
